US0D1018607S

(12) **United States Design Patent** (10) **Patent No.:** **US D1,018,607 S**
(45) **Date of Patent:** **** Mar. 19, 2024**

(54) **INTERIOR COMPONENT FOR
REFRIGERATOR**

(71) Applicant: **SAMSUNG ELECTRONICS CO., LTD.**, Suwon-si (KR)

(72) Inventors: **Hyunil Lee**, Suwon-si (KR); **Suyeon Park**, Suwon-si (KR); **Jungeun Park**, Suwon-si (KR); **Jaemin Lee**, Suwon-si (KR); **Seokwoo Kim**, Suwon-si (KR); **Junguk Shin**, Suwon-si (KR)

(73) Assignee: **SAMSUNG ELECTRONICS CO., LTD.**, Gyeonggi-Do (KR)

(**) Term: **15 Years**

(21) Appl. No.: **29/746,893**

(22) Filed: **Aug. 18, 2020**

(30) **Foreign Application Priority Data**

Apr. 17, 2020 (KR) 30-2020-0017162

(51) **LOC (14) Cl.** **15-07**

(52) **U.S. Cl.**

USPC **D15/89**

(57) **CLAIM**

The ornamental design for an interior component for refrigerator, as shown and described.

DESCRIPTION

FIG. 1 is a perspective view of an interior component for refrigerator, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines illustrating portions of the interior component for refrigerator form no part of the claimed design.

1 Claim, 7 Drawing Sheets
